CLAIM

The ornamental design for a catalytic heating panel, as shown and described.

DESCRIPTION

FIG. 1 is a front perspective view of a catalytic heating panel showing my new design;

FIG. 2 is a front elevational view thereof;

FIG. 3 is a right side elevational view thereof;

FIG. 4 is a left side elevational view thereof;

FIG. 5 is a top plan view thereof; and

FIG. 6 is a bottom plan view thereof.

The rear surfaces that are not shown are flat and plain. The pattern of perforations which is fragmentarily shown in FIGS. 1 and 2 is understood to repeat uniformly and continuously across the entire indicated area.

FIG. 1

FIG. 6

FIG. 2

FIG. 3
